UNITED STATES PATENT OFFICE.

JERRY C. CHAMBERS, OF DALEVILLE, ALABAMA.

PLOW.

1,113,150

Specification of Letters Patent.

Patented Oct. 6, 1914.

Application filed July 23, 1912. Serial No. 711,144.

To all whom it may concern:

Be it known that I, JERRY C. CHAMBERS, citizen of the United States, residing at Daleville, in the county of Dale and State 5 of Alabama, have invented certain new and useful Improvements in Plows, of which the following is a specification.

This invention relates to plows and has for its object the provision of a simple and 10 inexpensive construction whereby choking of the plow standard or beam will be effectually prevented.

The invention consists in certain novel features which are illustrated in the accompanying drawings and will be hereinafter 15 first fully described and then more particularly pointed out in the claims following the description.

In the drawings:—Figure 1 is a side elevation of a plow constructed in accordance with my invention; Fig. 2 is a horizontal section taken on the line 2—2 of Fig. 1; Fig. 3 is a detail view of a portion of the plow beam and standard.

25 In carrying out my invention, I employ a plow beam 1 which is preferably formed of metal and may be of any desired dimensions. The rear portion of the beam is carried upwardly, as indicated at 2, and carried rearwardly to merge into the standard 3 which is formed integral therewith. By 30 this construction a high arch 4 is formed over the plowshare 5 so that an accumulation of weeds, trash, or dirt will be accommodated and will not be held to the share by the beam to choke and impede the progress of the plow. The front edge or side of the standard is beveled toward its opposite 35 side faces, as indicated at 6, so that, as the plow is drawn over the field, the dirt and roots and other matter turned up and thrown against the standard will be deflected to either side and will not be permitted to lodge against the standard, as will 40 be readily understood. This beveled formation is carried around the under portion of the upwardly extended rear end of the beam, as shown at 7, so as to further prevent accumulation which would tend to choke the plow.

45 In the upper rear edge of the plowshare, a large recess or notch 8 is provided immediately adjacent the standard so that the roots and other material which would tend to collect upon the mold board and 50 against the standard will be permitted to 55

pass to the rear of the share and drop behind the same so that the progress of the share through the ground will be unimpeded. The standard is cut away on its front edge at its lower end to provide a seat 60 9 and a shoulder 10 against which the share is secured so that rocking of the share will be practically eliminated.

The bolts by which the share is secured to the standard and by which the several parts 65 of the share are secured together have their heads countersunk in the members of the share so that they will present no objections to the upward movement of the dirt turned from the furrow and consequently the plow 70 will have a light draft.

In its opposite side faces, the plow standard 3 is provided with recesses or seats 11 adapted to receive the ends of the handles 12 and the said recesses are deeper at their 75 front ends than at their rear ends so that the front edges of the handles will lie against the front walls of the said recesses and the outer sides of the handles will be flush with the sides of the standard, as 80 shown most clearly in Fig. 2, thereby presenting a smooth uninterrupted surface over which the material turned aside by the standard may pass.

It will be seen from the foregoing description, taken in connection with the accompanying drawings, that I have provided an exceedingly simple, strong, and durable plow by which accumulation of the matter turned up by the plow upon the mold-board 90 and against the standard will be effectually prevented and said material turned aside so that the plow may be easily drawn through the ground with a light draft.

What I claim is:—

1. In a plow, the combination of a beam arched at its inner extremity and terminating in a downwardly extending standard having substantially arcuate recesses formed in the sides thereof adjacent their lower 100 extremities, the inner face of said arched portion and the standard being beveled to form a cutting edge substantially straight throughout the greater portion of the length of the standard and handles secured in the 105 recesses formed in the standard, the fixed extremities of said handles being disposed substantially in alinement with the beam.

2. In a plow, the combination of a beam arched at its inner extremity and terminat- 110

ing in a downwardly extending standard having substantially arcuate recesses formed in the sides thereof, the inner face of said arched portion and the standard being 5 beveled to form a cutting edge, said recesses extending upwardly and opening through the rear edge of the standard and having their side walls converging toward the cutting edge thereof, and handles secured in 10 said recesses.

3. In a plow, the combination of a beam arched at its inner extremity and terminating in a downwardly extending standard having substantially arcuate recesses formed 15 in the sides thereof, the inner face of said arched portion and the standard being beveled to form a cutting edge terminating short of the free extremity of the standard to produce a seat defining a terminal shoulder, a share secured to the seat and bear- 20

ing against the shoulder, and handles carried by the standard.

4. In a plow, the combination of a beam arched at its inner extremity and terminating in a solid downwardly extending standard substantially V-shaped in cross-section 25 and having substantially arcuate recesses formed in the sides thereof, the inner face of said arched portion being beveled and forming with the inner face of the standard 30 a continuous cutting edge, said recesses having their side walls converging toward the cutting edge of the standard, and handles secured in said recesses.

In testimony whereof I affix my signature 35 in presence of two witnesses.

JERRY C. CHAMBERS. [L.S.]
